COMBINED RADIO RECEIVER-TAPE RECORDER UNIT OR SIMILAR ARTICLE

Ken Kawamura, Kadoma-shi, Osaka, and Minoru Ohwada Suita-shi, Osaka, Japan, assignors to Matsushita Electric Industrial Co., Ltd., Osaka, Japan, a corporation of Japan

Filed Oct. 31, 1968, Ser. No. 14,258

Claims priority, application Japan June 11, 1968

Term of patent 14 years

Int. Cl. D14—03

U.S. Cl. D56—4

FIG. 1 is a fragmentary front, top and right side perspective view of a combined radio receiver-tape recorder unit or similar article, showing our new design, the top left rear corner being broken away for convenience in illustration;

FIG. 2 is a left side elevational view;

FIG. 3 is a front elevational view; and

FIG. 4 is a rear elevational view thereof.

We claim:

The ornamental design for a combined radio receiver-tape recorder unit or similar article, as shown and described.
